UNITED STATES PATENT OFFICE.

DANIEL C. STICKRATH, OF OMAHA, NEBRASKA.

PORTABLE STREET SIGNALING DEVICE.

1,315,049.

Specification of Letters Patent. Patented Sept. 2, 1919.

Application filed March 29, 1919. Serial No. 286,171.

To all whom it may concern:

Be it known that I, DANIEL C. STICKRATH, a citizen of the United States, residing at Omaha, in the county of Douglas and State 5 of Nebraska, have invented certain new and useful Improvements in Portable Street Signaling Devices, of which the following is a specification.

This invention relates to a signaling device for use at street intersections and has for its object, broadly, to provide a standard centrally of the street crossing to be provided with "go and stop" signals to be operated remotely, or at the side of the street, 10 by a person who may observe and direct the movement of vehicles, and by means of devices under his control may readily cause a required movement of the signals, the principal features of utility being that an operator will not be exposed to inclement weather 15 and may observe the movements of vehicles better than a person at the middle of a street intersection, and the signal may be seen to better advantage by drivers of vehicles than the customary manual signaling 20 of a traffic officer.

The invention includes means for illuminating the signal at night and an automatically operated bell for use during day- 25 time and night, and also includes a feature relating to portability of both the signal-bearing standard and observation booth of the operator.

The novel features relating to the invention 30 are fully described herein and pointed out in the appended claims, and are illustrated in the accompanying drawings wherein,

Figure 1 is a broken away view showing 35 the standard and booth in side elevation, parts thereof being in section, a trench or underground conduit being shown in section. Fig. 2 is a sectional detail illustrating automatic bell-ringing mechanism. Fig. 3 is 40 a broken away sectional view showing the four signal arms employed and illuminating means therefor. Fig. 4 shows a coupling for a swing-post of the conduit with the operating-shaft. Fig. 5 is a broken away 45 detail relating to Fig. 2, showing a cam used in the automatic bell-ringing mechanism. Fig. 6 is a plan view of one of the rock- 50 levers used for actuating the cables in the conduit, being a detail relating to Fig. 1. Fig. 7 is a transverse section through one 55 of the signal arms.

Referring now to the drawing the invention is illustrated in connection with a conduit 8 which may be disposed in the ground or pavement 9. It may have any required 60 length to extend from an observation booth 10, preferably disposed at or near curb of a street intersection, to a hollow standard 11, at the center of a street intersection.

Numeral 12 indicates a vertical swing-post 65 having suitable bearings in the conduit and provided with a pair of opposed arms 13, its upper end having a head 15 provided with a recess 14 (Fig. 4) which is formed angular in cross-section for receiving the lower end 70 of a vertical shaft 16, the lower end of said shaft being angular in cross-section, so that a rotatable movement of the post 12 will be communicated to said shaft.

The shaft 16 traverses the standard and 75 rigidly mounted thereon near its upper end, are four hollow-signal arms arranged radially in pairs, as indicated at 17 and 18, the arms of a pair being disposed in line and substantially 90 degrees from the arms of 80 the other pair, each of the sides of one pair of arms bearing the words "Go," and each of the sides of the other pair bearing the words "Stop."

The vertical shaft 16 and the standard each 85 have adequate lengths so that the signal arms may be disposed at such a height that the signals may be conveniently seen by pedestrians and the drivers of vehicles, and since these parts are portable they are each constructed of two parts, as the parts *a* and *a'* 90 for the hollow standard and the parts *b* and *b'* for the shaft 16, the respective parts for each being suitably and removably connected at their inner ends.

The parts are so arranged that each pair of signal arms, while at rest, will be disposed in line with a street, providing the intersecting streets are disposed at right-angles, and since the words "Stop" appear upon both 100 sides of a pair of arms, the words "Go" operate as authority for a movement of traffic upon the other street, until the shaft 16 has been rotated 90 degrees.

Numeral 19 indicates a vertical operating 105 shaft within the booth 10. It has a part at its lower end which is angular in cross section, similar to the lower terminal for the shaft 16. Numeral 20 indicates a swing-post disposed in line with the operating shaft 110 and having bearings in the walls of the conduit, said post being provided with opposed

arms 21, as best shown in Fig. 6, similar to the arms 13 above described for the swing-post 12; and the upper end of the swing-post 20 is provided with a head 22 having a recess for receiving the lower end of the shaft 19, said recess being angular in cross-section, whereby a rotatable movement of said shaft will cause a corresponding movement of the post 20.

10 Numerals 23 indicate a pair of adjusting rods each being removably mounted in the end of an arm 21, its inner end being provided with a loop 24, and by use of a pair of cables 25, each being connected with a 15 loop 24 and with an arm 13 of the post 12, an operator using the operating-wheel α within the booth may have control for rotating the post 12, in either direction, in an 20 arc of 90 degrees for actuating the signal arms.

In order that an audible signal may be sounded simultaneously with the movement of the signal arms I provide a bell 26 and secure it upon the upper end portion of the 25 shaft 16. Numerals 27 indicate a pair of clappers for the bell, these being disposed in slots 28 formed in the upper and lower walls of the pair of signal arms 17. They 30 operate as rock-arms and are pivotally mounted as indicated at 29 upon the brackets 30, said brackets being disposed within and mounted upon the walls of said signal arms.

Numerals 31 indicate a pair of springs 35 for causing movements in one direction of the upper parts of the rock-arms or clappers 28 with considerable force against the bell.

Rigidly mounted upon the upper-end of the standard and below the signal-arms are 40 a pair of guides or cams 32 each having a curved wall c extending toward its convergent terminal and toward the shaft 16; and it will be understood that when a signal arm 17 swings in one direction, the rock-45 arms will be carried thereby, and since the lower end of a rock-arm will engage the wall c of the stationary cam, its lower end will be moved inwardly by the swinging movement of said signal arm until said lower end reaches the convergent end of the cam. The 50 rock-arm will then be released and its lower end will swing outwardly of the cam, its upper end moving against the bell by operation of the spring 31.

55 Numerals 33 indicate extensions for the lower ends of the rock arms 27 each having a hingeable connection with a rock-arm. As best shown in Fig. 7, guards or projections d are provided for these members, and it 60 will be understood that these extensions will not prevent free swinging movements of the signal arms. When the signal arm 17 swings in one direction to cause an extension 33 to engage the wall c of a cam, said extension 65 will be disposed in alinement with the rock-

arm on account of the engagement of the projections d , and after the extension 33 is released from the cam it may swing in one direction on account of said hingeable connection, to permit a swinging movement of 70 the signal arm in an opposite direction.

The provision of the audible signal is a great advantage since it directs attention to the moving arms. According to the present construction two clappers 27 and two 75 cams 32 are required. Since the signal arms rotate in arcs of 90 degrees members 27 will be actuated by the cams before the arms have completed their movement in one direction, and the audible signal operates to give an 80 early notice of a change in the direction of traffic. Members 27 are actuated in alternation, each operating to ring the bell while the signal arm in which it is mounted swings in one direction. Numerals 34 indicate a 85 resilient member, these being carried by the signal arms 17 and operating to disengage the clappers from the bell after each stroke.

In order that the cables 25 may be adjusted as to length, sleeves 35 are threaded upon the rods 23 which may be rotated for making said adjustment. Numerals 36 indicate a cover for a man-hole provided for the conduit to permit access thereto for making the 90 adjustments, and the booth is provided with 95 a trap-door 37 for use in connection with member 36. The standard, at its lower end is also provided with a door 38, convenient for making any required adjustments.

Since it may be desirable, upon occasion, 100 to remove and to replace the standard and the booth they have such proportions that they are readily portable, and when removed the heads 15 and 22 of the respective posts 12 and 20 will not become injured since they 105 do not project above the surface of the pavement.

In order that the signal arms may be illuminated at night they consist of rectangular box-frames having their sides provided with 110 transparent plates 39, incandescent lamps 40 being provided and suitably mounted therein. Any suitable arrangement for the electrical conductors may be made, as the pair of conductors 41 energized by any suitable 115 source of electrical supply, as the electrical battery 42. Numerals 43 indicate electrical contact-members which are insulated and which are mounted in recesses of a surface-plate 44 disposed in the pavement at the mid-120 dle of the street intersection.

The standard is provided with a base 45 having a pair of recesses formed therein in which are disposed a pair of insulated electrical contact-members 46; and at 47 and 47' 125 are indicated a pair of electrical conductors in electrical communication with the electrical contact-members 46 and with all of lamps 40, said conductors 47, as best shown in Fig. 3, being in electrical communication 130

with one of the electrical conductors 48 of each lamp since as best shown in Fig. 2, each conductor 48 is in electrical communication with a pair of electrical contact-members 49 which are insulated and are mounted in the inner end-walls of the signal arms, the conductors 47' being in electrical communication with one of the electrical conductors 50 for each lamp, each conductor 50 being in electrical communication with a pair of insulated contact-members 51 which are disposed above members 49 and are mounted in the inner end-walls of the signal arms.

It is appreciated that, when the standard 15 is placed in position, the electrical contact-members 43 and 46 must be in engagement in order that an electrical circuit will be established, but the parts are so proportioned that these contact-members are disposed 20 equi-distant from the head 15, so that they will enter into engagement when the shaft 16 is coupled with the post 12. Numeral 52 indicates an electrical switch, by means of which the electrical circuit may be broken, 25 when illumination of the signal arms is not needed. Numeral 53 indicates a hood suitably supported by radially disposed arms 54 carried by the shaft 16 for protecting the signal arms from rain or snow.

30 The two-part construction provided for the standard and the shaft 16 are features relating to portability, and they may be stored in the booth, when disconnected. Numerals 55 indicate insulated electrical 35 contact-members arranged in pairs for the standard, one member of each pair being mounted upon the section *b*, and the other member of each pair being mounted on the section *b'* of the standard, each of the electrical 40 conductors 47 and 47' therefore being a two-part construction but each operating as a single electrical conductor when the section *b* of the standard has been mounted on the section *b'*. Numeral 56 indicates a 45 bracket which is disposed within the standard *b'*, which supports the section *b* when mounted thereon.

While I have described construction in detail I do not wish to be understood as limiting myself to exactness in this respect, and changes in form, size, proportion and minor details may be made, in accordance with the appended claims.

I claim,—

55 1. In a portable signaling device, a stationary conduit, a post having journaled bearings and disposed within and transversely of the conduit, a shaft splined on the post, horizontally disposed arms projecting 60 radially from and rigidly mounted on the shaft, each being provided with indices, a second post having journaled bearings and disposed within and transversely of the conduit, a member connecting said posts, said 65 second post being adapted to have swinging

movements in an arc substantially of 90 degrees for causing corresponding movements of the first named post and said shaft.

2. In a street-signaling device, the combination with a conduit having a part disposed at substantially the middle of a street intersection and having a second part disposed remote therefrom, of an upright post journaled in the first named part of the conduit, an upright post journaled in the second part of the conduit, a cable connecting said posts, an upright shaft splined on the first named post, a stationary hollow standard circumscribing the shaft, a cam stationary with the standard, signal-arms provided with indices and disposed radially of and carried by the shaft, a resiliently mounted rock-arm mounted on a signal-arm, means for rotating the posts to cause a swinging movement of the shaft and signal arms in an arc substantially of 90 degrees and to cause the rock arm to move into engagement with the cam for sounding the bell.

3. In a portable signaling device, a conduit provided with electrical contact-members, electrical conductors in the conduit in communication with the electrical contact-members of said conduit, an upright post journaled in the conduit, an upright shaft 95 splined on the post, signal-arms carried by the shaft, each having opposed transparent parts and provided with indices, a hollow standard circumscribing the shaft and provided with electrical contact-members normally in electrical communication with the contact-members of the conduit, lamps between the transparent parts of the signal arms and provided with electrical conductors in communication with the electrical 100 contact-members of the standard, means to electrically energize the electrical conductors of said conduit, and means to rotate the post substantially 90 degrees for causing a 105 corresponding movement of the signal-arms. 110

4. A signaling device, comprising, in combination with a conduit having a man-hole and a cover for said man-hole, a post provided with transverse arms and journaled in the conduit, an upright shaft splined on said post, signal-arms disposed radially of and movable with the shaft, a second post, said second post being provided with transverse arms and disposed adjacent to said man-hole, cables connecting the transverse arms 120 of the first named post with the transverse arms of the second post, devices connected with the cables and disposed adjacent to the man-hole for making longitudinal adjustments of said cables, and means for rotating 125 the second post for causing a swinging movement of the first named post in an arc substantially of 90 degrees for causing a corresponding movement of said upright shaft.

5. In a signaling device for the purpose 130

described, the combination of a conduit provided with electrical contact-members, an upright post in the conduit and adapted to have revoluble reciprocation in an arc of 90 degrees, an upright shaft above the conduit and movable with the post, an alarm bell on the shaft, hollow arms provided with indices, said arms being disposed radially of and movable with the shaft, a hollow standard circumscribing the shaft and provided with electrical contact-members adapted to engage the contact-members of said conduit, a cam on the standard, lamps carried by said

arms and having electrical conductors in communication with the electrical contact-members of the standard, means to electrically energize the contact-members of said conduit, and a rock-arm movable with the shaft to engage the cam for sounding said alarm-bell.

In testimony whereof, I have affixed my signature in presence of two witnesses.

DANIEL C. STICKRATH.
